UNITED STATES PATENT OFFICE.

EDWARD T. BURROWES, OF PORTLAND, MAINE.

DESIGN FOR A BUFFER.

SPECIFICATION forming part of Design No. 30,056, dated January 24, 1899.

Application filed December 13, 1898. Serial No. 699,182. Term of patent 14 years.

To all whom it may concern:

Be it known that I, EDWARD T. BURROWES, a citizen of the United States, residing at Portland, in the county of Cumberland and State of Maine, have invented and produced a new and original Design for Buffers; and I do hereby declare the following to be a full, clear, and exact description of the same, reference being had to the accompanying drawings, forming a part thereof.

This invention relates to a new and original design for a buffer, and it is embodied in the device hereinafter described and claimed, and shown in the accompanying drawings.

15 In the drawings, Figure 1 is a perspective view. Fig. 2 is a central longitudinal vertical section.

20 In the drawings, A designates the stem portion, cylindrical in cross-section, having the inclined lower edges a. At the upper end of

the stem is a flat head portion B, the thickness of which is relatively less than the diameter of the stem. This head portion has a flat upper face and rounded or curved corners.

25 The essential feature of the design is the cylindrical stem portion having the flat head portion, substantially as shown.

Having thus described the design, what is claimed as new, and desired to be secured by Letters Patent, is—

The design for a buffer, substantially as shown and described.

In testimony whereof I affix my signature in presence of two witnesses.

EDWARD T. BURROWES.

Witnesses:

FRANK L. RICKER,
H. W. ROBINSON.
